UNITED STATES PATENT OFFICE.

JULIUS DORNETH, OF BERLIN, GERMANY.

AUTOMATIC DOOR-LOCKING DEVICE.

1,150,422.

Specification of Letters Patent.

Patented Aug. 17, 1915.

Application filed December 5, 1913. Serial No. 804,808.

To all whom it may concern:

Be it known that I, JULIUS DORNETH, a subject of the German Emperor, and residing at Berlin, Germany, have invented certain new and useful Improvements in Automatic Door-Locking Devices, of which the following is a specification.

My invention relates to improvements in automatic door locking devices which can be operated from the inside and the outside of the door, and more particularly my invention relates to improvements in door locking devices of that class, in which a rockable and longitudinally shiftable locking lever is adapted to be rocked over the door frame and door and locked by means of a holding member formed with an angular slot.

The object of the improvements is to provide a locking device of this class in which the locking lever is adapted to be shifted in the direction of its pivotal axis, and in which the holding member is provided with two slots or hooks which are disposed at different distances from the axis of the locking lever and in such a way, that in the elevated position the said locking lever permits the door to be slightly opened, for which purpose it is rocked at a certain angle by the door being opened and is simultaneously held in the slot or hook which is adjacent to its axis, while it completely locks the door when it is in its lowermost position.

For the purpose of explaining the invention several examples embodying the same have been shown in the accompanying drawings, in which the same letters of reference have been used in all the views to indicate corresponding parts.

In said drawings—Figure 1, is a front view of the inner side of a door provided with my improved locking means and showing the locking means in locking position; Fig. 2, is a similar view of the same parts showing the locking means with the locking lever in elevated position; Fig. 3, is a similar view showing the door partly opened and the locking means in the position in which it provides a safety device; Fig. 4, is a horizontal section of a detail of the locking means shown in Figs. 1 to 3; Fig. 5, shows respectively a side view and a cross-section of the upper part of the bail providing the main member of the locking means; Fig. 6, is a front view of a modification of the locking means showing the lock-

ing means in locking position, Fig. 7, is a similar view of the parts illustrated in Fig. 6 showing the door partly opened and the locking means in the position in which it provides a safety lock, Fig. 8, is a horizontal section on an enlarged scale showing a detail of the locking mechanism shown in Figs. 6 and 7, Fig. 9 is a detail, Figs. 10 to 12, show a further modification of the locking means, Fig. 10 being a front view Fig. 11 a side view and Fig. 12 a plan view of the mechanism, and Fig. 13, is a plan view showing a further modification.

Referring to the example illustrated in Figs. 1 to 5, a lever 4 in the form of a substantially U-shaped bail has a rocking support with its bent ends in an upper and lower bearing 2 secured to the frame of a door 1. The horizontal shanks 3 of the said bail provide the locking members. To the door 5 plates 6 are secured which at their inner or right hand ends 7 and at their outer or left hand ends 8 are bent forward and out of the plane of the door, the inner ends being in the form of hooks and the outer ends being provided with angular slots comprising horizontal and vertical branches 9 and 10. The shanks 3 are formed with reduced or flattened portions which are adapted to engage the slots 9 and 10.

In the locking position shown in Fig. 1 the bail engages with its horizontal shanks 3 in the slots 10 and behind the hooks 7 and 9 so as to prevent the door from being opened. In order to open the door it is necessary to lift the bail 4. This is done by means of a pin 11 secured to the bail about the middle thereof. A second pin 12 is secured to the lower one of the horizontal shanks 3 and it is in such a position that in the closed position of the door and in the locking position of the bail 4 it engages in a bore made in the lower one of the bearings 2. When the bail 4 is lifted the pin 12 is disengaged from the bore and when turning the bail the pin 12 slides over the upper surface of the bearing plate 2 and prevents the bail from falling downward. At the upper end of the bail 4 a spring 13 is provided which has the tendency to force the bail downward. The spring 13 is also preferably attached at one end to the bail 4 and at the other end to the bearing 2 in such manner as to have a tendency to turn the bail into the position shown in Fig. 2, whereupon the expensive tendency of the

spring 13 causes the bail to be pressed downward into the position shown in Fig. 1,—in locking engagement with the hooks 7 and 9 on the door.

5 For unlocking the locking mechanism and lifting the bail a key 15 is pushed through the door from without. On the door, adjacent to the pin 11 there is secured a bracket 18. On the bracket 18 is a pivoted arm 16 which 10 turns from a horizontal position to an upwardly inclined position, Fig. 2. The arm 16 is held in the horizontal position by spring pins 14 (Fig. 4) which are seated in the frame 18 and engage notches in the arm 16. The arm 16 is provided at its end with a beveled plate 17 (see Fig. 3). When pushing the key 15 into the door the spring actuated pins 14 are forced backward and into the position shown in Fig. 4, where- 15 upon by turning the key the arm 16 can be rocked upward. Thereby the bail 4 is lifted and rocked forward by the beveled plate 17 on arm 16 against the tension of spring 13 (which is relatively light), so that the 20 shanks 3 are disengaged from the hooks 7 and 9, and from the door, through the slots 10.

Above the bail a leaf spring 19 (Figs. 1 and 5) is secured to the door which at its 25 free end is connected by a string, chain or the like 20 with the upper end of the bail 4 and tends to rock the bail into the position shown in Fig. 3 in dotted lines, that is into the position which is opposite to the locking 30 position. The spring 19 is stronger than the spring 13, and overcomes the latter in turning the bail to unlocked position. The upper plate 6 is formed with a finger 21 which when closing the door presses on the 35 spring 19 so as to throw the same out of action. Therefore the spring 13 (which is comparatively weak) can come into action so as to rock the bail 4 into locking position. When the door is opened the finger 21 40 releases the spring 19, so that the latter rocks the bail into open or non-locking position, as explained above.

My improved locking mechanism may 45 also be used as a door securing or safety device. For this purpose a plate 24 is mounted on a pivot 23 provided below the lower end of the bail 4. When the plate is turned upward and into the position shown in Fig. 3, the said plate engages below the lower 50 end of the bail 4 and holds the same in lifted position with the pin 12 disengaged from the slot in the bearing 2. If now the door is opened from within, for example by means of a knob or handle 25, the bail is 55 rocked by the door without however completely leaving the slots 10, as there is no device (such as the cam 17) acting to turn the bail outwardly. As soon as the door has 60 been partially opened (and before the spring 19 can act to turn the bail outwardly 65

into unlocking position) the lug 8 which, when the door is closed, occupies a position which does not interfere with the upward and outward movement of the bail, when the door is partially open it (said lug 8) 70 juts out so as to engage the upper side of the arm 3 of the bail and prevents the arm 3 being raised upwardly the slight distance necessary to pass the lug 9 in its outward disengaging movement, thus maintaining 75 the engagement. The lug 8, furthermore, when the door is partially open engages partially over the arm 3 of the bail.

In order to prevent the door from being 80 opened from without, the bracket 18 can be rocked about a pivot 22. A leaf spring 29 engages with a lug 28 in a corresponding notch 28' of the bracket so as to hold the same in horizontal position. When lifting the leaf spring 29 with its lug 28 out of engagement with the notch 28' the bracket is turned by gravity about the pivot 22 and it is held by a stop 30 in the position shown in dotted lines in Fig. 1. Thereafter it is 85 not possible to lift the bail 4. The bail is provided with a pin or abutment 31 which is in position for engagement by the bracket 18 when the latter is rocked downward. Therefore the bail 4 can be lifted only after the bracket 18 has been rocked upward. Should the turning upward of the bracket 18 have been omitted when closing the door, the latter is automatically locked and it is not possible any more to unlock the same 90 from without. To avoid this a leaf spring 95 32 is provided which in the horizontal position of the bracket 18 is forced backward by the releasing lever 16, so that it can not come into action, and which projects from the door when the bracket has been rocked 100 downward, so that when closing the door it acts on the pin 11 before the shanks 3 engage in the slots 9, so that the door is not 105 locked. Furthermore it is not always necessary to provide a key 15 which can be 110 removed from the door. Instead of such a key an element such as a door knob, a lever, or the like may be provided which is 115 fixed to the door. This modification is 120 shown in Figs. 6 to 9. Also in this case the U-shaped locking bail 4' is lifted by means of a releasing lever 16' which engages below the said bail. For this purpose the bail is formed at its lower end with a collar 33 which is formed with a notch 34. Between the bail and the frame of the door a leaf 125 spring 35 is located which engages in the said notch with a nose as soon as the bail is lifted and turned and has assumed the position shown in Fig. 6 in dotted lines. At its upper end the bail 4' is provided with a screw-threaded part 36 which is engaged by a pin 37 secured to the frame of the door. As appears from Fig. 6, in the lowermost 130 position of the bail 4' the threads 36 are a

- suitable distance below the pin 37 and out of engagement therewith. When rocking the releasing lever 16' and lifting the bail 4', the latter is at first lifted without being turned, until its horizontal shanks 3' are at the rear of the slot 10' and the screw-threads 36 are engaged by the pin 37. Upon further rocking the lever 16' the bail 4' is lifted and rocked into the position shown in Fig. 6 in dotted lines in which it is held by the spring 35 engaging with its lug in the notch 34. When closing the door again, the releasing lever 16' forces the spring 35 backward, so that its lug is disengaged from the notch 34. Thereupon the bail 4 drops by gravity into its lowermost position, while being simultaneously turned by the screw threads 36 and the pin 37 so as to lock the door.
- In order that the bail may be used as a safety device, (as shown in Fig. 7) means must be provided as in the example described above to prevent the said bail from dropping from its intermediate position at the rear of the slot 10' into its lowermost position. As shown such means consist of a rocking pivotal plate 38 which is adapted to bear against a collar 39 formed on the bail.
- The bracket 18' which carries the releasing lever is acted upon by a spring 40 (Fig. 8) which has the tendency to rock the same and the lever 16' about a horizontal axis 41 and into the position shown in dotted lines in Figs. 7 and 9. This is normally prevented by means of a locking pawl 42. If the locking pawl is released by hand, the bracket 18' and the lever 16' are rocked upward and the lever 16' engages above a collar 43 of the bail 4', so that the bail 4' can not be lifted and the door can not be opened from without, because the lever 16' is out of its position for engagement by the lock mechanism.
- In the example illustrated in Figs. 10 to 12 instead of the spring 35 shown in Figs. 6 and 7 a spring actuated latch 44 is provided which holds the elevated bail 4' in elevated position, until upon closing the door the releasing lever 16' forces the latch 44 backward, whereupon the bail 4' moves downward while being turned. The bail is provided with horizontal shanks 3' corresponding to the shanks 3 of Figs. 1-5, and 3' of Figs. 6-9.
- 7' and 9' are hooks on the door similar to the hooks 7 and 9 of Figs. 1-5 and 7' and 9' of Figs. 6-9.
- The releasing lever 16' forms the nut arm of a safety lock, and in the example shown in the figures it is secured to the inner barrel 45 of a Yale lock 46 which as is known in the art can be turned only after a key 47 has been pushed into the lock.
- To the end of the releasing lever 16' a
- spring actuated hook 48 is pivoted, and a collar 60 formed on the bail 4' is formed with a corresponding notch 59. Ordinarily the hook 48 bears against the bail 4' without engaging in the notch 59, because in order to permit the same to engage in the notch it is necessary to slightly lift the lever 16', as appears from Fig. 11. If this is done by pushing the key 47 into the lock and slightly turning the barrel 45 and the nut 75 arm 16', the hook 48 engages into the notch 59, whereupon the bail 4' is locked and can be moved only by means of the key 47. Thereupon the key is turned back again and pulled out of the lock, and the door locking device can be opened from within and without only by means of the key which fits into the safety lock.
- The lock 46 is mounted on a horizontally shiftable slide 49 provided with guide slots 50 and 51, and it is held in position by means of a latch 52. In the normal position shown in Fig. 10 in full lines the lock can be operated from without by means of the key, but it can not be operated thereby in the position shown in dotted lines. In this position the slide 49 engages with a pin 53 in a slot 54 of the lever 3', so that the latter can not be lifted.
- In the example shown in Fig. 13 for locking the bail 4' the inner barrel 45' and the lever 16' can be fixed in two positions. The outer barrel of the lock is provided apart from the usual tumblers which are located in a vertical plane with tumblers which are mounted in an inclined plane. If now the inner barrel is turned by means of the key, until the tumblers controlled thereby are opposite to those of the outer barrel which are mounted in an inclined plane, and the key is pulled out of the lock, the lever 16' is locked in a second position in which it is engaged by a hook 55. Besides it is provided with a hook 56 which bears on a pin 57 of the lever 3'. This construction is preferable, because instead of the U-shaped bail 4' a single lever 3' is required, because in the locked position the releasing lever 16' has simultaneously the function of a locking lever such as 3 in Figs. 1 to 5.
- 3', 7' and 9' are similar to the parts 3, 7 and 9, 3', 7' and 9' and 3', 7' and 9' shown in the preceding figures.
- In order that the key can readily be inserted in the perpendicular position, a spring actuated pin 58 is provided within the outer barrel 46, which pin slightly projects a short distance into the inner barrel and holds the same in the proper position. If the inner barrel is turned by the key, the spring actuated pin may be provided in the inclined plane which is formed by the additional tumblers.
- I claim herein as my invention:
1. In a door securing device, the combination

- tion with a door member, and a frame member, of a locking device on one of said members mounted for rocking and axial movement and adapted to be rocked so as to extend over both members, holding means on the other one of the members disposed at different distances from the pivot of the locking member and in position for locking engagement with said locking device, a portion on the locking device arranged when opening the door for holding engagement with the holding means which is nearest the pivotal axis of the locking device, and means to shift and rock the locking device out of locking engagement with all the holding means.
2. In a door securing device, the combination with a door member, and a frame member, of a locking device on one of said members mounted for rocking and axial movement and adapted to be rocked so as to extend over both members, holding means on the other one of the members comprising hook shaped portions disposed at different distances from the pivot of the locking member and in position for locking engagement with said locking device, a portion on the locking device arranged when opening the door for holding engagement with the hook shaped portion which is nearest the pivotal axis of the locking device, and means to shift and rock the locking device out of locking engagement with both hook shaped portions.
3. In a door securing device, the combination with a door member, and a frame member, of a locking device on one of said members mounted for rocking and axial movement and adapted to be rocked so as to extend over both members, holding means on the other one of the members comprising hook shaped portions disposed at different distances from the pivot of the locking member and in position for locking engagement with said locking device, a portion on the locking device arranged when opening the door for holding engagement with the hook shaped portion which is nearest the pivotal axis of the locking device, normally inoperative means to hold the locking device in shifted position in which it is adapted to be engaged by the hook shaped portion which is nearest the pivotal axis of the locking device, and means to shift and rock the locking device out of locking engagement with both hook shaped portions.
4. In a door securing device, the combination with a door member, and a frame member, of a substantially U-shaped locking device on one of said members mounted for rocking and axial movement and adapted to be rocked so as to extend over both members, holding means on the other one of the members comprising hook shaped portions disposed at different distances from the

pivot of the locking member and in position for locking engagement with said locking device, normally inoperative means to hold the U-shaped locking device in shifted position with its horizontal shanks out of and its vertical part in position for locking engagement with the hook shaped portion which is nearest the pivotal axis of the locking device, and means to shift and rock the locking device out of locking engagement with both hook shaped portions.

5. In a door securing device, the combination with a door member, and a frame member, of a locking device on one of said members having a screwing movement and adapted to be rocked by its screwing movement so as to extend over both members, holding means on the other one of the members comprising portions in the form of hooks disposed at different distances from the axis of the locking member and in position for locking engagement with the locking device, a portion on the locking device arranged when opening the door for holding engagement with the hook shaped portion which is nearest the pivotal axis of the locking device, and means to lift and rock said locking device out of locking engagement with both hook shaped portions.

6. In a door securing device, the combination with a door member, and a frame member, of a locking device on one of said members having a screwing movement and adapted to be rocked by its screwing movement so as to extend over both members, holding means on the other one of the members comprising portions in the form of hooks disposed at different distances from the axis of the locking member and in position for locking engagement with the locking device, a portion on the locking device arranged when opening the door for holding engagement with the hook shaped portion which is nearest the pivotal axis of the locking device, means to screw said locking device out of locking engagement with both hook shaped portions, and means to arrest the locking device in an intermediate position in which its portion for holding engagement is in operative position.

7. In a door securing device, the combination with a door member, and a frame member, of a locking device on one of said members mounted for rocking and axial movement and adapted to be rocked so as to extend over both members, holding means on the other one of the members comprising hook shaped portions disposed at different distances from the axis of the locking member and in position for locking engagement with said locking device, a portion on the locking device arranged when opening the door for holding engagement with the hook shaped portion which is nearest the pivotal axis of the locking device, means to

shift and rock the locking device out of locking engagement with both hook shaped portions, and means to arrest said locking device in non-locking position.

5 8. In a door securing device, the combination with a door member, and a frame member, of a locking device on one of said members having a screwing movement and adapted to be rocked by its screwing movement so as to extend over both members, holding means on the other one of the members comprising portions in the form of hooks disposed at different distances from the axis of the locking member and in position for locking engagement with the locking device, a portion on the locking device arranged when opening the door for holding engagement with the hook shaped portion which is nearest the pivotal axis of the locking device, means to move said locking device out of locking engagement with both hook shaped portions, and means to arrest the locking device in an intermediate position in which its portion for holding engagement is in operative position.

25 9. In a door securing device, the combination with a door member, and a frame member, of a locking device on one of said members having a screwing movement and adapted to be rocked by its screwing movement so as to extend over both members, holding means on the other one of the members comprising portions in the form of hooks disposed at different distances from the axis of the locking member and in position for locking engagement with the locking device, a portion on the locking device arranged when opening the door for holding engagement with the hook shaped portion which is nearest the pivotal axis of the locking device, means to screw said locking device out of locking engagement with both hook shaped portions, and a spring actuated latch adapted to arrest said locking device in non-locking position.

40 10. In a door securing device, the combination with a door member, and a frame member, of a locking device on one of said members mounted for rocking and axial movement and adapted to be rocked so as to extend over both members, holding means on the other one of the members comprising hook shaped portions disposed at different distances from the pivot of the locking member and in position for locking engagement with said locking device, a portion on the locking device arranged when opening the door for holding engagement with the hook shaped portion which is nearest the pivotal axis of the locking device, and means adapted to be operated from the side of the door which is opposite to the securing device to shift and rock the locking device out of locking engagement with both hook shaped portions.

11. In a door securing device, the combination with a door member, and a frame member, of a locking device on one of said members having a screwing movement and adapted to be rocked by its screwing movement so as to extend over both members, holding means on the other one of the members comprising portions in the form of hooks disposed at different distances from the axis of the locking member and in position for locking engagement with the locking device, a portion on the locking device arranged when opening the door for holding engagement with the hook shaped portion which is nearest the pivotal axis of the locking device, and means adapted to be operated from the side of the door which is opposite to the securing device to screw said locking device out of locking engagement with both hook shaped portions.

12. In a door securing device, the combination with a door member, and a frame member, of a locking device on one of said members, mounted for rocking and axial movement and adapted to be rocked so as to extend over both members, holding means on the other one of the members comprising hook shaped portions disposed at different distances from the pivot of the locking member and in position for locking engagement with said locking device, a portion on the locking device arranged when opening the door for holding engagement with the hook shaped portion which is nearest the pivotal axis of the locking device, and means comprising a safety lock and adapted to be operated from the side of the door which is opposite to the securing device to screw said locking device out of locking engagement with both hook shaped portions.

13. In a door securing device, the combination with a door member, and a frame member, of a locking device on one of said members having a screwing movement and adapted to be rocked by its screwing movement so as to extend over both members, holding means on the other one of the members comprising portions in the form of hooks disposed at different distances from the axis of the locking member and in position for locking engagement with the locking device, a portion on the locking device arranged when opening the door for holding engagement with the hook shaped portion which is nearest the pivotal axis of the locking device, and means comprising a safety lock and adapted to be operated from the side of the door which is opposite to the securing device to screw said locking device out of locking engagement with both hook shaped portions.

14. In a door securing device, the combination with a door member, and a frame member, of a locking device on one of said

members mounted for rocking and axial movement and adapted to be rocked so as to extend over both members, holding means on the other one of the members, comprising 5 hook shaped portions disposed at different distances from the pivot of the locking member and in position for locking engagement with said locking device, a portion on the locking device arranged when opening the door for holding engagement with the hook shaped portion which is nearest the pivotal axis of the locking device, means to lock the locking device in locking position, and means to shift and rock the locking device out of 10 locking engagement with both hook shaped portions.

15. In a door securing device, the combination with a door member, and a frame member, of a locking device on one of said 20 members mounted for rocking and axial movement and adapted to be rocked so as to extend over both members, holding means on the other one of the members, comprising hook shaped portions disposed at different 25 distances from the pivot of the locking member and in position for locking engagement with said locking device, a portion on the locking device arranged when opening the door for holding engagement with the hook shaped portion which is nearest the pivotal axis of the locking device, means to lock the locking device in locking position, key operated means adapted to throw said locking 30 means for the locking device out of operation, and means to shift and rock the locking device out of locking engagement with both hook shaped portions.

16. In a door securing device, the combination with a door member, and a frame 40 member, of a locking device on one of said members, mounted for rocking and axial movement and adapted to be rocked so as to extend over both members, holding means on the other one of the members comprising 45 hook shaped portions disposed at different distances from the pivot of the locking member and in position for locking engagement with said locking device, a portion on the locking device arranged when opening the door for holding engagement with the hook shaped portion which is nearest the pivotal axis of the locking device, a safety lock, and a lever provided on the barrel of the safety lock and adapted when the barrel is turned 50 by means of the key to shift and rock the locking device out of locking engagement with both hook shaped portions.

17. In a door securing device, the combination with a door member, and a frame 60 member, of a locking device on one of said members having a screwing movement and adapted to be rocked by its screwing movement so as to extend over both members, holding means on the other one of the members comprising portions in the form of 65

hooks disposed at different distances from the axis of the locking member and in position for locking engagement with the locking device, a portion on the locking device arranged when opening the door for holding 70 engagement with the hook shaped portion which is nearest the pivotal axis of the locking device, a safety lock, and a lever provided on the barrel of the safety lock and adapted when the barrel is turned by means 75 of the key to lift and screw said locking device out of locking engagement with both hook shaped portions.

18. In a door securing device, the combination with a door member, and a frame 80 member, of a locking device on one of said members mounted for rocking and axial movement and adapted to be rocked so as to extend over both members, holding means on the other one of the members comprising 85 hook shaped portions disposed at different distances from the pivot of the locking member and in position for locking engagement with said locking device, a portion on the locking device arranged when opening the door for holding engagement with the hook shaped portion which is nearest the pivotal axis of the locking device, a safety lock, a lever provided on the barrel of the safety lock and adapted when the barrel is turned 90 by means of the key to shift and rock the locking device out of locking engagement with both hook shaped portions, a locking pawl on said lever adapted to lock the locking 95 device in locking position.

19. In a door securing device, the combination with a door member, and a frame member, of a locking device on one of said members having a screwing movement and adapted to be rocked by its screwing movement so as to extend over both members, holding means on the other one of the members comprising portions in the form of 100 hooks disposed at different distances from the axis of the locking member and in position for locking engagement with said locking device, a portion on the locking device arranged when opening the door for holding engagement with the hook shaped portion which is nearest the pivotal axis of the locking device, a safety lock, a lever provided on the barrel of the safety lock and adapted when the barrel is turned by means 105 of the key to screw said locking device out of locking engagement with both hook shaped portions, and a locking pawl on said lever adapted to lock the holding device in locking position.

20. In a door securing device, the combination with a door member, and a frame member, of a locking device on one of said members mounted for rocking and axial movement and adapted to be rocked so as to extend over both members, holding means 110 on the other one of the members comprising 115

hook shaped portions disposed at different distances from the pivot of the locking member and in position for joint locking engagement with said locking device, a portion on 5 the locking device arranged when opening the door for holding engagement with the hook shaped portion which is nearest the pivotal axis of the locking device, a safety lock, a lever provided on the barrel of the 10 safety lock and adapted when the barrel is turned by means of the key to shift and rock the locking device out of locking engagement with both hook shaped portions, and a locking pawl on said lever adapted when rocking 15 said lever to be thrown into locking engagement with the locking device placed in locking position.

21. In a door securing device, the combination with a door member, and a frame 20 member, of a locking device on one of said members mounted for rocking and axial movement and adapted to be rocked so as to extend over both members, holding means on the other one of the members comprising

hook shaped portions disposed at different 25 distances from the axis of the locking member and in position for locking engagement with said locking device, a portion on the locking device arranged when opening the door for holding engagement with the hook 30 shaped portion which is nearest the pivotal axis of the locking device, a safety lock adapted to be shifted out of position by its key and into locking engagement with the locking device, and a lever provided on the 35 barrel of the safety lock and adapted when the barrel is turned by means of the key to shift and rock the locking device out of locking engagement with both hook shaped portions. 40

In witness whereof, I have hereunto signed my name in the presence of two subscribing witnesses.

JULIUS DORNETH.
